(57) **CLAIM**

The ornamental design for an alignment guide, as shown and described.

DESCRIPTION

FIG. 1 is a front, top perspective view of an alignment guide comprising the new design;

FIG. 2 is a back, bottom perspective view of the design of FIG. 1;

FIG. 3 is a right side elevational view of the design of FIG. 1;

FIG. 4 is a left side elevational view of the design of FIG. 1;

FIG. 5 is a front elevational view of the design of FIG. 1; FIG. 6 is a back elevational view of the design of FIG. 1; FIG. 7 is a top view of the design of FIG. 1; and, FIG. 8 is a bottom view of the design of FIG. 1.

The broken lines are directed to the environment and are for illustrative purposes only; the broken lines form no part of the claimed alignment guide invention. The dash-dot-dot-dash broken lines shown in the figures represent an unclaimed boundary between claimed and unclaimed subject matter.

The relatively light uneven broken lines shown in the figures represent surface contour only.
